Brayton Richards

ATTORNEY.

UNITED STATES PATENT OFFICE

SAMUEL KUNSTADTER, OF HOMEWOOD, ILLINOIS, ASSIGNOR TO THE FORMFIT COMPANY, OF CHICAGO, ILLINOIS, A CORPORATION OF ILLINOIS.

BRASSIÈRE

Application filed July 17, 1931. Serial No. 551,319.

The invention relates to improvements in brassières, and has for its object the provision of an improved construction of this character which is capable of economical production and highly efficient in use.

Another object of the invention is the provision of a construction of the character indicated having special reinforcing means incorporated therein.

Another object of the invention is the provision of a construction of the character indicated having special cushioning means incorporated therein.

Other objects will appear hereinafter.

The invention consists in the combinations and arrangements of parts hereinafter described and claimed.

The invention will be best understood by reference to the accompanying drawings forming a part of this specification, and in which

Fig. 1 is a front view of a brassière embodying the invention;

Fig. 2 a partial rear view of the front portion thereof; and

Fig. 3 an enlarged partial section taken on line 3—3 of Fig. 1.

The embodiment of the invention illustrated in the drawings comprises two spaced supporter members, each formed of two pieces 10 and 11 of net material, joined together centrally by a vertical reinforcing seam 12. Arranged across the lower portion of each of the supporter bodies thus formed is a reinforcing strip 13, preferably of plush-like material having a multitude of closely adjacent hairlike cushioning projections 14 on the inner surface thereof, as best indicated in Fig. 3. Each of said reinforcing strips 13,

40 besides being stitched to the outer supporting body around its edges, is also stitched thereto by a plurality of substantially parallel lines of stitches 15, which further secure and reinforce the lower portions of said supporter members. The supporter members thus formed are joined together in spaced relation by a triangular piece of elastic webbing, the outer upper portion of which is covered by a tucked or puckered protecting and reinforcing piece 17, as shown.

The supporter members thus provided are equipped with suitable shoulder straps 17 of any usual or desired construction, connected at the back with a band 18 which is in turn connected with the supporter members 10—11, 55 so as to be capable of use as a brassière. The brassière thus provided will be found to be comfortable in wear and highly efficient in use.

The reinforcing strips 13 and stitches 15 give the supporter members sufficient strength and durability to perform their functions adequately and durably, and the nap or hairlike projections on said reinforcing strips afford a cushioning and ventilating effect which add materially to the comfort of the wearer. The specific form and arrangement of parts is a simple and effective one for the purpose.

While I have illustrated and described the preferred form of construction for carrying my invention into effect, this is capable of variation and modification without departing from the spirit of the invention. I, therefore, do not wish to be limited to the precise 75 details disclosed, but desire to avail myself of such variations and modifications as fall within the scope of the appended claims.

Having thus fully described my invention, what I claim as new and desire to secure by 80 Letters Patent is:

1. A brassière having a plurality of breast-receiving pockets each provided with an outer network body, each body having a reinforcing strip secured to the interior thereof across 85 the lower portion, each strip having on its inner surface hair-like nap standing out from the base thereof for contacting and supporting engagement with the breasts.

2. A brassière having a plurality of breast-receiving pockets each provided with an outer network body, each body having a reinforcing strip secured to the interior thereof across 95 the lower portion by stitching, each strip having on its inner surface hair-like nap standing out from the base thereof for contacting and supporting engagement with the breasts.

3. A brassière having a plurality of breast-receiving pockets each provided with an outer network body, each body having a rein- 100

forcing strip secured to the interior thereof across the lower portion by stitching, each strip having on its inner surface hair-like nap standing out from the base thereof for contacting and supporting engagement with the breasts, a connecting member for said pockets and said strips being secured to said connecting member along diverging lines by portions of said stitching.

10 In witness whereof, I have hereunto set my hand this 11th day of June, 1931.

SAMUEL KUNSTADTER.
